ATTORNEY.

UNITED STATES PATENT OFFICE

2,476,427

OVERLAPPING WIRE ENGAGING DEVICE

Francis F. Melvin and Joe O. Stevens, Elwood,
Ind.; said Stevens assignor to said Melvin

Application July 15, 1946, Serial No. 683,618

4 Claims. (Cl. 287—58)

1

This invention relates to means for maintaining a garment stretching device in extended or retracted positions at which the device may be selectively shifted. The primary object of the invention is to provide retention means which may be operated readily by gripping two members such as between the thumb and index finger to release the retention means and have these members simultaneously afford means for shifting apart one member from another to produce the extended condition of the shaping device. In the form of the invention herein shown, the invention is applied to a stretching frame such as would be used for shaping slacks and the like while drying.

The above indicated object and many others will become apparent to those versed in the art in the following description of the invention as illustrated in the accompanying drawing, in which,

Fig. 1 is a view in side elevation of a forming frame to which the invention is applied;

Fig. 2, a detail in top plan view of the securing means;

Fig. 3, a view in section on a line 3—3 in Fig. 2;

Fig. 4, a detail in plan view of the securing means from the opposite side of that shown in Fig. 2;

Fig. 5, a view in section on a line 5—5 in Fig. 4;

Fig. 6, a detail in transverse section on a line 6—6 in Fig. 1;

Fig. 7, a detail in top plan view of a wire end guide structure; and

Fig. 8, a transverse section on the line 8—8 in Fig. 1.

Like characters of reference indicate like parts throughout the several views in the drawing.

While the invention may be applied to a wide range of devices wherein there are members one extensible from the other, the invention is illustrated herein is applied to a simple stretching or forming frame wherein there are two wire members 10 and 11 having respectively a top leg 12 turned over the leg 13 and a lower leg 14 turned over the leg 15. The legs are so positioned as to be in parallel alignment respectively and substantially in sliding contact one with the other, the legs 12 and 15 being above respectively the legs 13 and 14. On each outer end of the legs 12 and 14 is a flattened curved end portion 16 provided with a hole 27 through which the other adjacent leg may freely slide. Thus the two wires 10 and 11 may be adjustably shifted one toward the other to an inner limiting position as determined by the lengths of the upper and lower legs, 55

2

and they also may be carried outwardly one from the other to extended positions.

A generally V-shape spring 17 is slotted as at 18 and 19 to receive through those slotted portions both legs 12 and 13. Each slot is sufficiently long to permit the pinching one toward the other of the downturned ends 20 and 21 of the spring members 17 toward vertical positions to assume some such position as indicated by the dash lines in Fig. 3, in which position the legs 12 and 13 may be freely shifted one over the other. The transverse widths of the slots 18 and 19 are limited to substantially the diameters of the legs 12 and 13 (both the same) plus a slight clearance 15 for a sliding fit. The lengths of the slot exceed the combined diameters of the legs 12 and 13 whereby releasing the legs 20 and 21 to the full line spread apart positions will cause the top and bottom edges of the slots 18 and 19 to grip opposite 20 sides of the legs 12 and 13 in planes diagonally positioned in reference to the axes of the legs 12 and 13, all in a manner very effectively gripping those legs and holding them against longitudinal travel one in respect to the other. Therefore, 25 when the two legs 20 and 21 are gripped such as between one's thumb and index finger to release the legs 12 and 13, the leg 13 may be shifted along the leg 12 while the spring 17 is so gripped, and simple release of the legs 20 and 21 will cause the spring 17 to retain the legs in the positions at the time of release.

To facilitate the shifting of the wire legs 12 and 13, one along the other, one of the legs, herein shown as the leg 13, is provided with spaced 35 abutments 28 and 29 between the spring legs 20 and 21, whereby the spring legs 20 and 21 when pinched one toward the other may strike either abutment as the direction of movement may be to carry the wire 13 along therewith as the spring 40 17 may be shifted along the wire leg 12. In other words, the spring legs 20 and 21 serve as means to move the wire leg 13. In the present showing, these abutments 28 and 29 constitute shoulders at the ends of a wire length 30 offset from the axis of the wire leg 13, Fig. 4. These abutments 45 are preferably near the end portion of the wire leg 13.

In the same manner a second spring 23 is provided to interengage the lower legs 14 and 15, the spring 23 being inverted in position as compared to the spring 17 so as to provide its legs 24 and 25 in upwardly extending directions. In all other respects, it is an exact duplicate of and operates in the same manner as that described 50 in reference to the upper spring 17, and the leg 15

is provided with spaced abutments 31 and 32 between the spring legs.

While we have herein shown and described our invention in the one best form as now known to us, it is obvious that structural changes may be employed and different modes of securing the spring member to the particular leg may be used, all without departing from the spirit of the invention, and therefore, we do not desire to be limited to that precise form beyond the limitations as may be imposed by the following claims.

We claim:

1. In an adjustable frame having a pair of wirelike members, one longitudinally slidable along the other, a member interengaging device comprising a generally V-shaped leaf spring having a slot in each leg thereof, both of said members being inserted through both of said slots, each of said slots being shaped and sized to cause opposed marginal end edges of the slots to be normally urged by the spring against opposing sides of said members when said legs are in positions oppositely oblique from lines normal to said members; each of said legs having sufficient lengths beyond said slots and being so spaced apart in their member engaging positions to afford finger operated grips; and an abutment on one of said members between said legs whereby pinching of one of said legs toward the other and attempting to push thereby said spring along said members will shift the abutment carrying member longitudinally of the other and the release of said legs will secure both members fixed one in respect to the other against further shifting.

2. In an adjustable frame having a pair of wire-like members longitudinally slidable one along the other, an integral end portion of one member being provided with an eye through which the second member is slidably guided; a leaf spring generally V-shaped to have normally diverging legs; each of said legs being provided with an elongated slot therethrough, the length of which slot exceeds the combined thicknesses of said members; both of said members being inserted through both of said slots; and an abutment on said second member straddled by said spring legs; said legs normally gripping said members by edges of said slots to hold the members against longitudinal travel one along the other; whereby pinching said legs one toward the other releases said gripping and shifting of the spring along said one member will carry therealong said second member by reason of the presence of said abutment.

3. In an adjustable frame having a pair of wire-like members longitudinally slidable one along the other, an integral end portion of one

member being provided with an eye through which the second member is slidably guided; a leaf spring generally V-shaped to have normally diverging legs; each of said legs being provided with an elongated slot therethrough, the length of which slot exceeds the combined thicknesses of said members; both of said members being inserted through both of said slots; and an abutment on said second member straddled by said spring legs; said legs normally gripping said members by edges of said slots to hold the members against longitudinal travel one along the other; whereby pinching said legs one toward the other releases said gripping and shifting of the spring along said one member will carry therealong said second member by reason of the presence of said abutment; said member integral end portion consisting of a flattened pierced end bent substantially normal to the axis of that member to extend laterally therefrom.

4. In an adjustable frame having a pair of wire-like members longitudinally slidable one along the other, an integral end portion of one member being provided with an eye through which the second member is slidably guided; a leaf spring generally V-shaped to have normally diverging legs; each of said legs being provided with an elongated slot therethrough, the length of which slot exceeds the combined thicknesses of said members; both of said members being inserted through both of said slots; and an abutment on said second member straddled by said spring legs; said legs normally gripping said members by edges of said slots to hold the members against longitudinal travel one along the other; whereby pinching said legs one toward the other releases said gripping and shifting of the spring along said one member will carry therealong said second member by reason of the presence of said abutment; said abutment consisting of a bend in the second member having a length limiting the travel of said spring legs toward each other to substantially that travel required for giving a full release of said gripping.
